ARTHUR E. WRIGHT Inventor

By Richard B. Owen Attorney

UNITED STATES PATENT OFFICE.

ARTHUR E. WRIGHT, OF GARDNER, ILLINOIS.

ROOF-FRAMING DEVICE.

Application filed July 3, 1922. Serial No. 572,680.

To all whom it may concern:

Be it known that I, ARTHUR E. WRIGHT, a citizen of the United States, residing at Gardner, in the county of Grundy and State 5 of Illinois, have invented certain new and useful Improvements in Roof-Framing Devices, of which the following is a specification.

My invention relates to improvements in 10 attachments for steel squares.

An object of my invention is to provide an attachment for an ordinary steel square for determining the length of ordinary hip and jack rafters, the bevel cuts of jacks and 15 hips and the difference in length of jacks for any pitch of roof.

A further object of my invention is to provide an attachment for an ordinary square, whereby the square may be used either as a 20 square or a bevel.

A still further object of my invention is to provide an attachment for a square whereby the attachment may be adjusted in any desired position on the square and held in 25 such position.

A still further object of my invention is to provide an attachment for an ordinary steel square which is strong, durable, simple and inexpensive in construction.

Other objects and advantages of the 30 invention will become apparent during the course of the following description.

In the accompanying drawings forming a part of the specification and in which like 35 numerals are employed to designate like parts throughout the same,

Figure 1 is a top plan view showing my invention applied to an ordinary steel square,

40 Figure 2 is a section on line 2—2 of Fig. 1, Figure 3 is a top plan view of the strip shown in Fig. 2,

Figure 4 is a section on line 4—4 of Fig. 1,

45 Figure 5 is a detail view of the strip as shown in section in Fig. 2,

Figure 6 is a section on line 6—6 of Fig. 1, and

Figure 7 is a top plan view of the strip shown in cross section in Fig. 4.

50 In the drawings wherein for the purpose of illustration is shown the preferred embodiment of my invention, the numeral 10 represents the ordinary square. The numerals 11 and 12 designate strips adapted to be mounted on the square 10 and slide thereon. The strip 11 is provided with lips 13

and 14 and also a hinge 15 to which is hinged a member 16 which forms one part of the telescopic arm 17. The strip 12 is provided with lips 18 and a hinge 19 on which is 60 mounted the other member 20 of the arm 17. Mounted on the arm 20 on the end near the hinge 16 is a bolt 21 on which is mounted a spring catch 22 to hold the arm 17 in any desired position. A thumb nut 23 is mounted 65 on the bolt 21 to hold the spring arm 22 in position.

In use, my device is used in conjunction with an ordinary square. By reason of the telescopic arm 17, the strips 11 and 12 may 70 be slid along the respective arm of the square 10. The attachment may be carried in any desired position by means of its spring arm 20, bolt 21 and thumb nut 23. It will thus be seen that I have provided a very useful 75 combined square and bevel particularly for use in the smaller lumber or building work, for example, a carpenter desires to build a roof of any pitch, the bevel should be set accordingly and the rafters could then be 80 easily laid out with a bevel for both ends, and the slide of the sections 17 and 20 in the center giving the length of rafter, the number of inches to the foot, and the bevel for the lumber of the gables, as well as the studding 85 in the gables all without changing the bevel.

It is to be understood that the form of my invention herewith shown and described is to be taken as the preferred embodiment of the same and that various changes in the 90 shape, size and arrangement of parts may be resorted to without departing from the spirit of my invention or the scope of the subjoined claims.

Having thus described my invention, I 95 claim:

1. The combination with a square, a telescopic arm, a hinge mounted on each end of said arm, lips made integral with the hinge to adapt the arm to be slidably mounted on 100 said square, and a spring arm mounted on said telescopic arm to engage the hinge and to hold the telescopic arm in any desired position.

2. The combination with a square, slidable 105 hinge members mounted on the arms of said square, and a telescopic arm connected to said hinge members, and a spring arm mounted on said telescopic arm to engage one of said hinges to hold the same in adjustment.

3. The combination with a square, a hinge 110

mounted on each end of said telescopic arm, lips made integral with the hinges, one of said hinges being provided with lips engageable with one side of the arm of a square only, the other of said hinges having lips carried thereby engageable with both edges of the arm of a square, said hinge members being slidably mounted on the arms of said square, and means carried by said telescopic arm to hold the slidable hinges in the desired 10 adjustments.

4. The combination with a square, clips slidably mounted on the arm of said square,

hinge members carried by said clips and movable therewith, a telescopic arm hingedly connected to said hinge members, and a spring arm mounted on said telescopic arm to engage one of said hinge members and to hold the telescopic arm in the desired adjustment. 15

In testimony whereof I affix my signature in presence of two witnesses.

ARTHUR E. WRIGHT.
